INVENTOR

Alfred J. Trigwell

BY John A. Oranith

HIS ATTORNEY

UNITED STATES PATENT OFFICE.

ALFRED J. TRIGWELL, OF SAN JOSE, CALIFORNIA.

TRACTOR.

1,267,825.

Specification of Letters Patent. Patented May 28, 1918.

Application filed September 5, 1916. Serial No. 118,380.

To all whom it may concern:

Be it known that I, ALFRED J. TRIGWELL, a subject of the King of Great Britain, and a resident of San Jose, in the county of 5 Santa Clara and State of California, have invented certain new and useful Improvements in Tractors, of which the following is a specification.

My invention relates to tractors, and particularly to that portion of the driving mechanism comprising the track and the sprockets upon which said track is mounted.

It is the object of my invention to provide a track in which the numerous small parts may be eliminated. In those forms of track now commonly used the numerous plates or shoes are connected in such a manner as to offer a multitude of wearing surfaces with their attendant difficulties and 15 to provide a great number of parts of various shapes and sizes that not only add greatly to the first cost of the track but also renders the track constantly subject to repair. It is, therefore, the object of my invention to so simplify the construction of 20 of the track that any broken part may be quickly and easily replaced with a new part, and that the wearing surfaces above referred to may be practically eliminated and consequently provide a track that may be properly called frictionless.

With the above and other objects in view, the invention consists in the novel and useful provision, formation, construction, combination and relative arrangement of parts as hereinafter described and shown in the accompanying drawing, in which,—

Figure 1 is a side elevation of a portion of a tractor showing my improved track in 40 position, parts being broken away.

Fig. 2 is an enlarged section on line A—A of Fig. 1.

Fig. 3 is an enlarged section on line B—B of Fig. 1.

Fig. 4 is a plan view of the inner surface of the track, part being broken away.

Fig. 5 is a sectional view through a counter-sunk plate or shoe.

Similar characters of reference refer to 50 similar parts throughout the several views.

Referring now more particularly to the drawings, 1 indicates a portion of a tractor frame upon which are mounted sprockets 2

and 3. Sprockets 2 and 3 are provided with a number, in this case 8, of transverse 55 grooves 4 equally spaced about the outer circumference thereof, and are also provided with three annular parallel channels 5 formed in their outer or wearing surfaces. The track proper, which forms the principal 60 subject matter of this invention, consists of three cables 6 carrying a plurality of shoes 7 secured thereto by bars 8 and bolts 9. When the track is assembled as shown in part in Fig. 4, the shoes 7 are secured to 65 cables 6 so that their longer edges are adjacent to each other, and said cables 6 are so arranged that the ends of each cable approach each other between different shoes from any other cable as indicated at 10, 11 70 and 12 respectively. The track being now placed on sprockets 2 and 3 and given the proper tension by adjustment 13, it is ready for use. Frame 14 and idlers 15 as well as adjustment 13, may be provided substantially the same as those now in common use. Idlers 15 should, however, carry a belt 16 to engage bars 8 and thereby provide a smooth running surface for the same. In attaching cables 6 to shoes 7 it is desirable 80 to drill shoes 7 as indicated at 17 and to tap bars 8 as indicated at 18, then bolts 9 may be screwed into bars 8 thereby drawing the same up tightly against shoes 7 and securely gripping cables 6. Inasmuch as bolts 9 may 85 project a distance through bars 8, and also since sand or other foreign matter may tend to collect in grooves 4, it is desirable to provide a number of openings, as 19, in each of said sprockets to receive said projecting 90 bolts and to permit the expulsion of said foreign matter therethrough when bars 8 enter said grooves 4.

It is understood, of course, that while I have shown and described in detail one particular method of construction I do not wish to confine myself to the particular construction shown and described as various forms of shoes may be used, such as shown in Fig. 5 in which the outer face is counter-sunk to 95 receive the bolt head, and various methods may be used for securing the shoes to the cables. Also while I have shown and described cables for connecting shoes 7, a chain or other continuous element may be used depending upon the exigencies of manufac- 100 105

ture. The number of channels in each sprocket would of course correspond with the number of connecting elements used.

Having thus described my invention 5 what I claim as new and desire to secure by Letters Patent, is:—

1. In a tractor, a pair of sprockets, each sprocket having a plurality of transversely positioned grooves and a plurality of annular channels formed in the outer circumference thereof, and an endless track adapted to be carried by said sprockets, said track 10 comprising a plurality of flexible connecting elements adapted to engage said channels, and a plurality of juxtaposed shoes secured to said connecting elements, each shoe having a bar secured to its inner surface adapted to engage one of said transverse grooves.
2. In a tractor, a pair of sprockets, each sprocket having a plurality of transversely positioned grooves and a plurality of annular channels formed in the outer circumference thereof, and an endless track adapted to be carried by said sprockets, said track 15 comprising a plurality of flexible connecting elements adapted to engage said channels, and a plurality of juxtaposed shoes secured to said connecting elements, each shoe having a bar secured to its inner surface adapted to engage one of said transverse grooves.
3. A traction belt composed of a plurality of independent juxtaposed shoes having substantially flat inner surfaces, a plurality of cables along which said shoes are arranged, and a plurality of bars, each bar having a flat side for engagement with the flat inner surface of said shoes, and a plurality of transverse grooves formed in said flat side

for spacing and engaging said cables, and means for detachably securing one of said bars to the inner surface of each shoe.

4. In a tractor, a pair of sprockets, each 45 sprocket having a plurality of transversely positioned grooves and a plurality of annular channels formed in the outer circumference thereof, and an endless track adapted to be carried by said sprockets, said track 50 comprising a plurality of flexible connecting elements adapted to engage said channels, and a plurality of juxtaposed shoes secured to said connecting elements by means of a bar secured to the inner surface of each shoe 55 and adapted to tightly engage said connecting elements, said bars being adapted to engage said transverse grooves in said sprockets, and each of said connecting elements having its ends approach each other between 60 a different pair of shoes from any other connecting element.

5. In a tractor, a pair of sprockets, each sprocket having a plurality of transversely positioned grooves and a plurality of annular channels formed in the outer circumference thereof, and an endless track adapted to be carried by said sprockets, said track 65 comprising a plurality of flexible connecting elements adapted to engage said channels, and a plurality of juxtaposed shoes secured to said connecting elements by means of a transversely grooved bar secured to each of said shoes and adapted to tightly engage 70 said connecting elements, said bars being 75 adapted to engage said transverse grooves in said sprockets.

In testimony whereof I have hereunto affixed my signature this 29th day of August, 1916.

ALFRED J. TRIGWELL.
